MACHINE FOR FINISHING TUBULAR STEREO-TYPE PRINTING PLATES

Louis S. Tyma, Jr., Hinsdale, and John M. Gvozdjak, Cicero, Ill., assignors to Miehle-Goss-Dexter, Incorporated, Wilmington, Del., a corporation of Delaware

Application June 20, 1957, Serial No. 666,976

20 Claims. (Cl. 29—21)

The present invention relates in general to a machine for finishing tubular stereotype printing plates.

Stereotype plates of the tubular type wherein a single plate encompasses almost the entire cylinder leaving only a gap or slot between the straight ends or edges, are ordinarily finished by first cutting the unfinished tubular plate to the proper length and beveling the cut-off end of the plate, then machining the inner cylindrical surface thereof to a specified diameter. Heretofore it has been customary to provide lock-up means in this inner surface adjacent to the straight edges of the plate. The plates are engaged and locked up securely on the plate cylinders by lock-up mechanism carried by the plate cylinder, which is effective in cooperation with the lock-up means on the plate to apply circumferential tension to stretch the plate and draw it tight around the cylinder. One lock-up method which has been in widespread use, employs grooves in the inner surface of the tubular plate and lock-up mechanism on the plate cylinder which is engaged in these grooves for locking up the plate. A plate cylinder equipped with lock-up mechanism which operates in this manner is disclosed in Foster Patent No. 2,047,364, dated July 14, 1935, for example. This invention relates particularly to finishing tubular plates adapted to be locked up on printing cylinders constructed as illustrated in the aforesaid Foster patent.

It is a general object of this invention to provide a method and means for finishing tubular stereotype printing plates to a high degree of machining accuracy at a reasonable production rate.

In order to maintain high quality standards which entails maintaining machining accuracy in the finishing operations, means are provided for positioning the plate precisely and holding it securely in the finishing machine during the finishing operations. Moreover, due to the tubular form of the plate, apparatus of a special character is provided which is capable of carrying out the finishing operations involving cutting metal from the inside of the tubular plate member while it is held in the machine.

In more detail, it is an object of this invention to provide means for supporting the tubular stereo plate in the plate finishing machine while the finishing operations are carried out. These finishing operations involve boring the inner surface of the tubular plate to a specified diameter and broaching plate lock-up grooves in the finished inner surface of the plate adjacent the straight edges thereof.

Accordingly, it is an object of this invention to support a tubular stereotype printing plate in the finishing machine for rotation about the longitudinal axis of the plate so that the inner surface thereof may be bored to a specified diameter expediently and with precision. Another object is to provide a rotatable sleeve for supporting the plate on the machine frame, and clamping apparatus carried by the sleeve for securing the plate inside the sleeve wherein the clamping apparatus is self-actuated. A further object is to provide for operating the clamping apparatus for clamping and unclamping a plate, by means

2

mounted on the machine frame, this clamping apparatus being operable when the sleeve is held against rotation in a predetermined angular position.

A further object of the invention is to provide a method and means for finishing tubular stereotype printing plates wherein plate lock-up grooves are machined adjacent the straight ends or edges of the plate. With this form of plate, cylinder lock-up mechanism like that shown in the aforementioned Foster patent engages the plate by means of the grooves, the jaws of the mechanism pressing against the side walls of the grooves to place the plate under tension and pressing it closely to the cylinder throughout its area.

It is another object to provide for machining the plate lock-up grooves with a broaching tool which is power driven. Another object is to lock the rotatable sleeve against rotation for supporting the plate rigidly so that the broaching operation may be carried out expediently.

Another object is to incorporate in the finishing machine an indexing assembly effective for the dual purpose of locking the sleeve against rotation and preventing end-wise movement of the plate, especially important during the broaching operation due to the heavy forces applied by the broaching tool against the plate during this operation.

Another object is to provide a plate stop and plate ejecting apparatus which is effective for locating the plate axially in the sleeve so that it may be cut off to the proper length, and which is effective for partially ejecting the plate from the sleeve when the plate is unloaded from the machine following the completion of the finishing operations.

Other objects and advantages will become apparent as the following description proceeds, taken in connection with the accompanying drawings, in which:

Figure 1 is a view in side elevation of a stereotype plate finishing machine constructed in accordance with the present invention;

Fig. 2 is a top plan view of the machine shown in Figure 1;

Figs. 15 and 16 are sectional views taken similarly to Fig. 14 with the plate stop and plate ejecting mechanism in different operating positions;

Figs. 17—21 are diagrammatic sequence views illustrating the power driven boring and broaching apparatus

carrying out the operations involved in finishing a tubular plate;

Figs. 22-25 are enlarged detail views of the individual plate clamps embodied in the plate clamp apparatus;

Figs. 26-29 are enlarged detail views illustrating the 5 guide bar, cutting heads, and driving mechanism therefor; and

Figs. 30, 31 are views illustrating the chain drive for the cutting links.

While the invention is susceptible of various modifications and alternative constructions, a preferred embodiment has been shown in the drawings and will be described in detail. It should be understood, however, that there is no intention to limit the invention to the specific form disclosed, but on the contrary, the intention is to cover all modifications, alternative constructions and equivalents falling within the spirit and scope of the invention as expressed in the appended claims.

General machine organization

By way of preliminary to a detailed discussion of the machine illustrated in the drawings, a brief description of the machine, its purpose, and its functions is here provided. This machine provides means for preparing a tubular stereotype printing plate for use on a printing press by machining the inner surface of the plate to a specified diameter and cutting lock-up grooves in the inner surface of the plate adjacent the straight edges. A finished plate which has been prepared in this manner is shown in Fig. 9. Accordingly, referring to Figure 1 of the drawings, an unfinished plate may be loaded in the machine by sliding the plate inside a rotatable annular sleeve 20 where it may be clamped, so that the sleeve supports the plate on the machine frame 21 for rotation about the longitudinal axis of the plate.

In accordance with the invention, means are provided for locating the plate properly in the sleeve prior to clamping, this same means also serving as a plate ejecting mechanism for ejecting the plate from the sleeve after the plate has been finished. Herein a movable plate stop 22 (Fig. 15) is provided for locating the plate in a predetermined axial position. This movable stop 22 also serves as a plate ejecting mechanism for ejecting the plate from the sleeve after the plate has been finished (Fig. 16) and for this purpose is slidable within the sleeve for engaging and shifting the plate.

For clamping the plate securely within the rotatable sleeve so that the appropriate finishing operations can be carried out on the plate, further in accordance with the invention, plate clamps 23 mounted in the sleeve are provided for engaging the edges of the plate and applying clamping pressure for expanding the plate into uniform contact with the inside of the sleeve, these plate clamps 23 being self-actuated by springs contained as part of the plate clamp assembly within the sleeve. Moreover, in keeping with the intention, to operate the plate clamp apparatus, the machine is provided with lock-up mechanism 24 which is mounted on the machine frame and is controllable by the machine operator for clamping and unclamping the plate. With the plate located properly in the sleeve and clamped securely, the sleeve 20 is rotated by a power drive 25 so as to enable the finishing of the plate.

Before the finishing operations are carried out, the plate is first trimmed to length. This is customarily a cut-off operation which may be performed by an appropriate cut-off tool 26.

With the plate thus prepared the finishing operation wherein the inner surface of the plate is bored to a specified diameter may be carried out on the machine. This boring operation may be performed by an appropriate boring tool, such as by a power driven apparatus 27 which is constructed as part of the machine. Reference is made to the copending application, Serial No. 667,005, filed June 20, 1957, of Corson Walter Chase and Louis

S. Tyma, Jr. entitled Power Driven Broaching and Boring Apparatus for Plate Finishing Machines for a complete description of this apparatus. In general, this power driven apparatus 27 incorporates a boring head 28 (Figs. 2 and 27) which is slidably mounted on ways on a cutter guide bar 29. The guide bar 29 is fixedly mounted above the main part of the machine frame so as to extend through the annular sleeve, thus positioning the boring head 28 for engaging the inner surface of the plate. In order to bore the plate the boring head is moved axially of the plate as it rotates.

Then, further in accordance with the invention, it is proposed to perform an additional finishing operation wherein lock-up means are machined in the inner surface 15 of the tubular plate in the form of grooves 30 extending the full length of the plate adjacent the straight edges 31. In the finishing machine of the present invention, the grooves 30 are broached by a broaching head 32 also supported by the guide bar 29, and which comprises an element of the power driven apparatus 27. This element is also described in detail in the copending application just referred to. This broaching head 32 is forced axially of the plate while the plate is held rigidly on the machine frame within the sleeve 20, which is held against rotation 20 during this broaching operation.

For locking the sleeve against rotation and for holding the plate rigidly against endwise movement during the broaching operation, when the forces applied to the plate tending to shift it are very great, in accordance with 30 the invention the sleeve is indexed to a predetermined angular position and the plate is held in that position and against axial movement by means of an indexing assembly 35 mounted on the frame.

Upon more specific reference to the drawings, it will 35 be understood from the foregoing that the invention is shown as embodied in an illustrative tubular stereotype printing plate finishing machine, shown in Figure 1. As illustrated more particularly in Figures 1-3, the machine is made with a bed 21 or frame the main part 41 of 40 which is protectively covered. On this main part of the machine there is supported the rotatable annular sleeve 20 which is employed for holding the tubular plate during the finishing operations. The sleeve, in the present instance, is supported for rotation by a bracket 42 which is bolted to the frame so that the legs 43, 44 of the bracket 45 extend vertically above the main part of the frame. The bracket legs 43, 44 are bored to receive aligned bushings 46 which hold the annular sleeve 20 for rotation.

Supported lengthwise of the bed or frame and located 50 substantially over the center of the machine so as to extend through the annular sleeve 20 is the power driven apparatus 27 for boring and broaching the inner surface of a tubular plate held within the sleeve 20. As may be seen in Figures 1 and 3, the bed or frame 21 of the machine 55 is raised which provides means for supporting a transverse bracket 49 at the loading end 58 of the machine mounting one end of the guide bar 29.

So that the tubular plate can be slid over the bracket 49 and into the sleeve 20 during the loading operation, 60 the neck 51 of the bracket is made slightly narrower than the slot in the plate, as shown in Fig. 3. On this guide bar 29 the boring head 28 and the broaching head 32 are 65 slidably mounted in way surfaces 52, 53 which are machined in the lateral faces of the guide bar. A chain drive 54 is provided for moving the heads in the desired manner for carrying out the machining operations. At the left-hand end of the machine as viewed in Figures 1 and 2, the guide bar 29 is supported directly on the machine frame 21. At this same end of the machine a drive 70 sprocket 56 which is mounted in an adjustable bracket 58, is provided to supply means for moving the chain and powering the cutting heads. By adjusting this bracket 58 the drive sprocket may be shifted to obtain proper tension in the chain 54. The chain is also trained around an idler sprocket 59 which is journaled on a shaft 60

mounted in the cutter bar 29 a short distance from the bracket 49 supporting the guide bar at the loading end of the machine. A drive motor M-1 mounted on the main frame 41 of the machine is employed to drive the drive sprocket 56.

In carrying out the invention, for turning the plate for boring, the sleeve which supports the plate is driven by a power drive 25. For this purpose the sleeve is provided around its outer periphery with adjacent sprocket teeth forming a sprocket 61. A source of power for driving the sleeve is mounted within the protectively covered main part 41 of the machine frame 21 and in the present instance comprises a motor M-2, a drive shaft 63, and a drive sprocket 64 on the drive shaft 63 which is coupled to the annular sleeve by a chain 65 trained around the two sprockets. A brake 66 for locking the drive shaft against turning may be provided, although other mechanical expedients may be used if so desired. The function of the brake 66 is to prevent the sleeve 20 from turning, and appropriate controls are provided on the machine for releasing and applying the brake 66 at the option of the machine operator.

Plate clamp apparatus

Turning now to the plate clamp apparatus (Figs. 5-8 and 22-25) in greater detail, the structural aspects of the sleeve 20 and the plate clamps indicated by the general reference numeral 23, will now be considered. In the present instance, the sleeve 20 is of annular construction and includes a cylinder with a collar 76 at one end and an integral flange 77 at the other end, which present annular, radially extending shoulders 78 which abut the outer faces, respectively, of the legs 43, 44 of the bracket 42 on which the sleeve 20 is rotatably supported. On the end of the sleeve 20 facing the loading end 50 of the machine, a hand wheel 80 is mounted so that it may be grasped by the machine operator and turned for indexing the sleeve 20 to place it in a predetermined angular position for the broaching operation and so that the sleeve is appropriately positioned for operation of the plate clamps. In the present instance, two sets of plate clamps are provided for engaging the plate and expanding it tightly against the inside diameter of the sleeve 20. For receiving the sets of plate clamps, a T slot 83 is machined in the sleeve 20 so that the slot opens to the inside of the sleeve. A spacer block 85 which slides in the T slot divides the slot lengthwise into separate compartments which receive the sets of plate clamps. The plate clamps are formed as sub-assemblies which comprise fixed jaws 86A, C and jaws 86B, D which are slidably mounted on the fixed jaws. Each sub-assembly is mounted in the sleeve by sliding it in the T slot until positioned against the spacer block 85, and end plates serve to hold the sub-assemblies in place within the sleeve. Within the sleeve the plate clamp jaws are urged in plate clamping direction by spring force obtained from a series of coil springs 87 contained in bored holes 88 in the movable jaws and seated against rectangular bars 89, 90 which are part of the sub-assembly. These flat, rectangular bars 89, 90 (Figs. 5, 7) seat on a shoulder of the T slot, thus acting as a base for the springs. Under the present arrangement the fixed jaws 86A, C of each set of clamps are arranged within the T slot so that the plate engaging portion extends inwardly of the inside surface of the annular sleeve 20. The movable jaws 86B, D lie side by side and nest with the fixed jaws 86A, C, respectively, with the fixed jaws towards one side and the movable jaws towards the other side of the sleeve 20. Each movable jaw includes a pair of shorter jaw extensions 91 which extend through openings 91' in the fixed jaw to project inwardly of the sleeve. The openings 91' in the fixed jaw appear clearly in the elevational Fig. 23 and the two shorter jaw extensions 91 of the movable jaw are visible in Fig. 25. These openings 91' in the

fixed jaw are wider than the jaw extensions and allow relative movement between the jaws. To limit the expansion of the springs 87 and thus the outward movement of the movable jaws 86B, D, a series of machine screws 92 are provided which are threaded into the bottom of the bored holes in the movable jaws passing through chamfered holes 93 in the bars 89, 90, respectively. When the sets of jaws are compressed together and forced into nested relation so as to unclamp the tubular plate, as shown in Fig. 7, the machine screws 92 may push out behind the rectangular bars into the cavity 94 formed by the lateral portion of the slot. Since the sleeve must be rotated during certain of the machining operations, the clamping mechanism is contained in the sleeve assembly so that it rotates with the sleeve. Accordingly, the coil springs 87 are effective to maintain the jaws of the clamping apparatus in engagement with a plate within the sleeve, for expanding the tubular plate into uniform contact with the inside of the sleeve.

In accordance with the present invention, an operating mechanism 24 mounted on the machine frame is provided for actuating the plate clamp apparatus housed in the sleeve. For this purpose a lock-up lever 95 mounted on the frame is movable into engagement with a series of bell crank levers 96A-D which are mounted on the sleeve 20. Under this arrangement the outer surface of the sleeve has four spaced openings 97A-D through which the bell crank levers 96A-D project to extend outwardly of the sleeve. In the present instance, the bell crank levers 96A-D are pivoted to blocks 98A-D which are bolted to the sleeve within the spaced openings 97A-D provided in the sleeve for receiving these levers. Each bell crank, as shown in Figs. 6, 7 is generally triangular in shape and has rollers 99, 101 at the corners. The inner roller 99 is positioned for engagement with the movable jaw, and the outer roller 101 is located outwardly of the sleeve for engagement by the lock-up lever mechanism 24 mounted on the machine frame. As shown in Fig. 8, the lock-up lever 95 extends substantially the length of the sleeve 20 and is pivoted on the shafts 105 having four spaced wear plates 106A-D for engagement with the spaced bell cranks. Referring to Fig. 6, the coil springs 87 are in an expanded condition and the movable jaws 86B, D of both sets of plate clamps are forced into engagement with one plate edge so that with the other plate edge contacting the fixed jaws 86A, C the tubular plate is expanded into uniform contact with the sleeve. To retract the movable jaw, the bell crank is pivoted clockwise as shown in Fig. 6 so as to engage the inner roller 99 with the movable jaw of the plate clamp apparatus and compress the springs forcing the jaws together. The longitudinal spacing of the openings in the sleeve and the extent which the bell crank levers project outwardly of the sleeve is such that as the sleeve turns the projecting bell crank levers pass without contacting any portion of the machine frame 21 or the bracket structure 42 for supporting the sleeve. Moreover, the lock-up lever 95 is biased by a spring 108 away from the sleeve and out of engagement with the bell crank levers 96A-D mounted on the sleeve.

For actuating the lock-up lever, a cam 109 and cam follower 110 arrangement may be utilized. In the present instance the cam 109 is supported on a vertical control shaft 111 and engages a roller 110, which functions as a cam follower, mounted on the lever 95. The vertical control shaft 111 is journaled in a bracket 112 bolted to the machine frame, and the control shaft is turned by a control handle 113 which lies over the top of the machine and is fastened to the shaft by a yoke 114 which permits the handle to be raised and lowered as it is turned. The configuration of the cam is illustrated in Fig. 14. The clamping apparatus contained in the sleeve may be operated to clamp and unclamp a plate by turning the control shaft 111.

Plate stop and plate ejector

Further in accordance with the invention, the mechanism for operating the plate clamp apparatus is effective both for that purpose and for the purpose of operating the plate stop and plate ejector 22. Referring particularly to Figs. 3, 6 and 14-16, the control shaft 111 which carries the cam 109 for operating the plate clamps, also carries a gear segment 120 which is effective to operate the plate stop and plate ejector 22. For locating the tubular plate within the sleeve 20, the plate stop 22 is positioned adjacent the end of the sleeve 20 so as to be engaged by the end of the tubular plate as it is inserted in the sleeve. The plate is thus located in a predetermined axial position relative to the sleeve. An arm 121 supports the plate stop 22, the arm in turn being supported by a rack shaft 122 which is carried so as to move lengthwise of the machine in horizontal openings 123 which are machined in the sleeve mounting bracket 42. As the control handle 113 and gear segment 120 are rotated, the gear segment by engaging the rack teeth 124 shifts the shaft which in turn shifts the plate stop 22. In the prescribed and normally followed sequence of operations, for loading a plate on the machine the operating handle 113 is placed in a loading position L (Figs. 14, 15) wherein: (1) the plate stop 22 is positioned to stop the plate, and (2) the plate clamps 23 are compressed so as to present clearance for the slot in the plate (Fig. 7). This loading position of the control handle is an intermediate position determined by the pin 125 (Fig. 3) fastened on the under side of the handle in relation to the stop 126 formed on the bracket 112. The loading operation is carried out by sliding a tubular plate past the end bracket 49 supporting the guide bar 29 and over the rest 127 on the end of the guide bar. After the tubular plate has been loaded in the sleeve 20, the handle 113 is moved to the operating position O of Fig. 15 by raising the handle so that the pin 125 clears the stop 126, and moving it clockwise. This movement of the control handle simultaneously effects release of the lock-up lever and, consequently, operation of the plate clamps 23 to clamp the plate, and shifts the plate stop 22 away from the end of the plate so as to insure against contact while the plate is turning. The plate is then ready for the finishing operations.

After the plate has been machined and is to be unloaded from the machine, the control handle 113 is moved to an unloading position U (Fig. 15, 16). For partially ejecting the tubular plate from the sleeve 20, the plate stop 22 is guided past the plate locating position of Figs. 14 and 15 into the inside of the sleeve. The stop 22 thus functions as a plate ejector forcing the plate from the sleeve so that it projects from the sleeve a sufficient distance to be removed manually. The stop 22 is guided in its movement by a slide plate 128 mounted on the upper surface of the guide bar (Figs. 1, 6).

Sleeve indexing

After the boring operation has been completed, in keeping with the invention, the sleeve 20 may be rotated by hand and indexed to a given angular position so that the plate may be broached. For this purpose, the loading end of the sleeve 20 is provided with a hand wheel 80 which may be gripped by the machine operator and turned to rotate the plate. For locking the plate in position for broaching, an indexing assembly indicated generally at 35, is provided. This assembly also provides means for holding the plate against endwise movement as the broaching head is forced through the plate.

As shown in Figs. 2 and 11-13, at the loading end of the machine and supported on the bed 21 there is provided a mounting frame 135 for the indexing assembly. In general this mounting frame comprises spaced plates 137, 138 which extend horizontally from the back of the machine forward to a position adjacent the end of the rotatable sleeve 20. These plates are joined by a

common web 139 at the back of the machine. The lower plate 137 is bolted to the bed 21 of the machine frame and the upper plate 138 is held by means of the web 139. Support for the indexing assembly 35 is provided by a vertical shaft 140 which seats in alined bores in the plates. The shaft extends through the plate stop 141, the main element of the assembly. This plate stop is pivotable about the axis of the shaft 140 between a position as shown in Fig. 11 where it blocks longitudinal movement of the sleeve during the broaching operation, and an out-of-the-way position as shown in Fig. 13. The outer edge of the plate stop 141 is curved and slotted, and the broaching cutters pass through the slots 145 at the end of the broaching stroke. In addition to the plate stop 141, the assembly 35 includes a wedge plate 146 which is slidably mounted on the stop so as to be positionable behind camming edges 148 on the upper and lower mounting plates. The wedge plate is actuatable by a control handle 150 to force solidly against the end of a tubular plate in the sleeve 20 to hold the plate against endwise movement. For this purpose the wedge plate 146 is located between the plate stop 141 and the locking handle 150 and slides on the stop. The sliding movement is guided in a straight line by a pin 157 fixed in the stop 141 which fits into a groove 158 in the wedge plate. Upon rotating the actuating handle counter-clockwise as shown in Fig. 12, the wedge plate is caused to slide to the chain line position where it clears the ends of the bracket plates outwardly beyond the camming edges 148. The sliding movement is caused by a pin 159 moved by the actuating handle which rides in a second slot 160 in the wedge plate. The outer position of the wedge plate is shown in Fig. 12. Upon clockwise movement of the actuating handle the wedge plate is moved to its inner position as shown in the same figure to cam the plate stop 141 against the tubular plate within the sleeve and hold it in that position.

In addition to holding the plate against endwise movement, the indexing assembly provides means for locking the sleeve 20 and thus the plate against rotation. In the position of the assembly shown in Fig. 11 an index pin 161 is inserted in an index pin socket 162 in the sleeve. Referring also to Fig. 4, this index pin socket 40 162 is formed in an adjustable socket member 163 which is mounted in a recess 164 in the wheel. It may be adjusted by an adjusting screw 165 which may be fixed in position by a set screw 166 accessible to the outside of the wheel. With this arrangement the sleeve 45 162 may be set and held precisely for broaching.

Power driven apparatus for boring and broaching

For finishing the inner surface of a plate clamped within the sleeve 20 there is incorporated in the machine a power driven boring and broaching apparatus 27 which is supported on the machine frame 21 for engagement with the inner surface of the plate. This is described completely in the copending application, Serial No. 667,005, filed June 20, 1957, of Corson Walter 55 Chase and Louis S. Tyma, Jr. entitled Power Driven Broaching and Boring Apparatus for Plate Finishing Machines. A brief description of the operation of the apparatus is included at this point to complete the description of the present invention.

60 A boring head 28 and a broaching head 32 are slidably mounted for longitudinal movement along the guide bar 29 so as to present cutters for engagement with the inner surface of the plate. For mounting the boring and broaching heads the lateral faces of the guide bar 29 are machined with longitudinal channels or ways 52, 53 which extend substantially the full length of the guide bar. These way surfaces on opposite sides of the guide bar thus extend parallel to the inner surface of a plate clamped within the sleeve and are provided 65 so that the boring head may be slidably mounted for

movement lengthwise of the guide bar and the plate, on one side of the bar, and likewise the broaching head on the opposite side of the guide bar. As previously described, a chain is employed for moving the heads, and as will be evident from Figs. 17-21, certain of the links of the chain are employed for engaging the broaching and boring heads. In both machining operations the cutting stroke entails movement of the cutting heads from an initial position adjacent the drive end of the bar, the length of the plate, to a point beyond the plate adjacent the idler sprocket. The heads are returned to the initial position in a return stroke. In the present instance the movements of the cutting heads both in the cutting stroke and return stroke are performed by pusher links A, B, C borne by the chain. Referring to Figs. 17-21, these are diagrammatic views illustrating the progressive steps involved in finishing the plate, and portray the movements of the chain and the different positions of the pusher links which engage the cutting heads. It will be understood that the driving of the chain may be under the control of an operator at all times, or it may be partially or completely automatically controlled. The successive operations involved in finishing a plate will be described as though each were separately controlled.

The first of the sequence views, Fig. 17, depicts the tubular plate after it has been loaded in the machine by locating and clamping it in the sleeve. At this stage both cutting heads are stopped in the initial position. At this point in the operation the sleeve 20 is driven and the cut-off tool 26 is employed for cutting off the tail (T) (Fig. 10). The plate is then stopped for removal of the tail.

Next, the plate is bored. For this operation the sleeve again is driven to turn the plate. Referring to Figs. 17 and 18, the chain is driven in the direction of the arrows to move the boring head through the plate in the cutting stroke. When the cutting stroke is ended the chain is stopped (Fig. 18), and the drive for the sleeve is also stopped so that the plate may be indexed for the broaching operation. At this stage pusher links B, C are at the loading end of the sleeve and pusher link A at the other end of the sleeve. The pusher link B has completed moving the boring head through the sleeve and the broaching head has been left in its initial position.

The sleeve is then indexed to a given angular position, as by means of the hand wheel 80 on the loading end of the sleeve, and the chain is driven to return to its initial position, where it is shown in Fig. 19. In the present instance, the plate indexing assembly 35 is provided for holding the sleeve 20 and thus the plate against rotation, and it also serves the purpose of holding the plate against endwise movement during the broaching operation. For this reason, the indexing assembly 35 is mounted at the loading end of the sleeve so as to hold the plate against the heavy forces of the broaching head which in the broaching operation is moved through the sleeve from its initial position near the drive end of the bar towards the loading end of the machine.

Accordingly, plate lock-up grooves are then broached in the plate by driving the chain as shown by the arrows in Fig. 20, so as to force the broaching head through the plate. During the broaching stroke, pusher link C has moved to shift the boring head in a return stroke as will be evident from Fig. 20. This figure depicts the chain and cutting heads when the chain has stopped following the broaching stroke.

For returning the broaching head to its initial position, the chain is reversed and driven in the direction of the arrows of Fig. 21. For transmitting this movement of the chain to the broaching head, the same pusher link A which was effective to perform the broaching stroke is employed to move the broaching head through the return stroke. For this purpose the broaching head is latched to the pusher link A by means of a latch mechanism 200.

Referring to Fig. 14, this mechanism comprises a latch arm 201 pivotally mounted at the rear of the broaching head 32 and having a transversely arranged head 201A. During the cutting stroke the head 201A is adapted to drop down behind the pusher link A and, therefore, the head is formed to slide in the dovetail channel 53 in the guide bar 29. In order to insure that this occurs a camming finger 202 is positioned to engage the upper surface of the head 201A (Fig. 26).

10 In the present instance the pusher link A is made of links which replace standard outside connecting links of the chain. These links of the pusher link A comprise plates which extend outward of the chain and have alined slots facing the broaching heads (Fig. 14). The alined slots fit over the rear edge of the broaching head allowing the latch arm 201 to hook behind the rear edge of the plates and effectively latch the pusher link and head together. As a result the broaching head is captive with the chain during the cutting and return stroke while means are provided for enabling the chain to be free for movement beyond the end of the return stroke.

This means is effective so that when the broaching head returns to the initial position (Fig. 14), the head 201A of the latch arm is automatically disengaged (Fig.

25 30) to free the pusher link A and allow it to travel around the drive sprocket with the chain. For disengaging the latch mechanism, at the drive end of the bar 29 a slanted camming surface 211 which is effective to raise the latch arm 201 is presented by a cam block 212 fastened on the way surface. For camming engagement with the block, the head 201A is formed with an oblique surface 213 which engages the block as the broaching head reaches the end of the bar. The cam block 212 is thus effective as the head is pulled up on the block, to raise the latch arm clear of the pusher link. This permits the pusher link A to travel with the chain. Accordingly, this link performs the dual functions of pushing the broaching head through the cutting stroke and 40 of pulling the broaching head through the return stroke. The other pusher links B, C in the chain serve merely to push the boring head, one of said links (B) pushing the head through the cutting stroke and the other (C) pushing the head through the return stroke. No latch mechanism is necessary for connecting these links (B, C) and the chain and none is provided. The links are, therefore, rectangularly shaped plates replacing the standard connecting links of the chain. The height of these plates is such that the link formed thereby extends 45 outwardly of the chain sufficiently to engage the boring head. These links are appropriately spaced in the chain in order to carry out the prescribed functions.

We claim as our invention:

1. In a machine for finishing tubular stereotype printing plates and having a frame, the combination comprising, 55 a rotatable member defining a cylindrical reference surface at least as large as the outside diameter of the tubular plate, and means for clamping the plate in said rotatable member with its outside surface lying in and in uniform contact with said reference surface, said rotatable member providing means for turning the plate for boring, and means carried by the frame and engageable with said rotatable member for locking said rotatable member rigidly against rotation for holding the plate so that plate lock-up grooves may be machined in the inner surface of the plate adjacent the straight edges of the plate.

2. In a machine for finishing tubular stereotype printing plates and having a frame supporting a cutting tool which engages the inner surface of the plate, the combination comprising, means for supporting the plate for engagement by the cutting tool including a sleeve having an inside diameter at least as large as the outside diameter of the tubular plate, and means for clamping the plate in said sleeve including plate clamp members carried by the

sleeve between the straight edges of the plate, one of said members being fixed on said sleeve and having a jaw for engaging the plate along one straight edge, another of said members being nested with and slidably mounted on said one fixed member and having a jaw for engaging the plate along the other straight edge, a plurality of compression springs acting on said slidably mounted member for urging the members into engagement with the plate straight edges for applying clamping pressure to the plate thus expanding the plate into uniform contact with the sleeve, a bell crank pivotally mounted on the sleeve for rocking movement about an axis parallel to the axis of the sleeve and engageable with said slidably mounted member, for moving the latter against the springs and out of engagement with the plate edge, and an actuating member pivotally mounted on said frame for movement transverse to the axis of the sleeve and into engagement with said bell crank for moving said bell crank to release the clamping pressure.

3. In a machine for finishing tubular stereotype printing plates and having a frame, the combination comprising, means for rotating the plate about its longitudinal axis including an annular member rotatably mounted on the machine frame, said member having an inside cylindrical surface at least as large as the outside diameter of the tubular plate, means for clamping the plate in said annular member by expanding the plate against said reference surface including nested plate clamps carried by an annular member between the straight edges of the plate, a first one of said plate clamps being fixed on the member for engagement with one of the plate straight edges, and another of said plate clamps being slidably on said first one of said plate clamps out of nested relation into engagement with the other of the plate straight edges, a compression spring for urging said plate clamps out of nested relation and into engagement with the plate edges respectively and for applying clamping pressure to the plate, a bell crank pivotally mounted on the rotatable member for rocking movement about an axis parallel to the axis of the annular member and engageable with said slidably clamp for forcing said plate clamps into nested relation against the force of said spring, and means pivotally mounted on said frame for movement transverse to the axis of the annular member and into engagement with said bell crank for actuating said bell crank to withdraw said plate clamps out of engagement with the plate edges releasing the clamping pressure and enabling the resiliency of the plate to draw the plate inwardly away from the inside surface of the annular member to release the plate so that it may be removed from the member.

4. In a machine for finishing tubular stereotype printing plates and having a frame, the combination comprising, means for supporting the plate for rotation about its own axis including a member rotatably mounted on the frame, said member defining a cylindrical reference surface, means carried by the member for clamping the plate against said surface for rotation with said member, and means for locating the plate lengthwise of its own axis relative to the member, said latter means having a plate locating position of engagement with the plate and an operating position out of plate engagement, and means connecting said plate clamping means and said plate locating means so that the latter means is moved between its positions as an incident to operating said means for clamping the plate.

5. In a machine for finishing tubular stereotype printing plates and having a frame, the combination comprising, means for supporting the plate for rotation about its own axis including a member rotatably mounted on the frame, said member defining a cylindrical reference surface, means carried by the member for clamping the plate against said surface for rotation with said member, a movable plate locating stop mounted on said frame for movement between a plate locating position of engagement with said plate wherein the plate is arcuately lo-

cated lengthwise of its own axis relative to the member, and an operating position out of plate engagement, and means for moving said stop from its plate locating position to its operating position as an incident to operating said means for clamping the plate.

6. In a machine for finishing tubular stereotype printing plates and having a frame supporting a cutting tool for machining the inner surface of the plate, the combination comprising, means for supporting the plate for rotation about its own axis including a member rotatably mounted on the frame, said member defining a cylindrical reference surface, means carried by the member for clamping the plate against said surface for rotation with said member, a movable plate locating stop mounted on said frame for movement between a plate locating position wherein the stop locates the plate lengthwise of its own axis relative to the member for the machining operation, an operating position wherein the stop is located out of plate engagement so that the plate rotates without interference during the machining operation, and an ejecting position, means for moving said stop to its operating position from its plate locating position as an incident to clamping the plate for rotation with said member, and means for moving said stop to its ejecting position from its operating position as an incident to unclamping the plate whereby the plate is partially ejected from the member.

7. In a machine for finishing tubular stereotype printing plates and having a frame, the combination comprising, means for supporting the plate for rotation about its own axis including a rotatable member mounted on the frame, plate clamps carried by the member operable for clamping the plate thereto, a stop mounted on said frame for adjustment between a plate locating position wherein the stop locates the plate lengthwise of its longitudinal axis relative to the member for a machining operation, and an operating position wherein the stop is located out of plate engagement so that the plate is free to rotate without interference during the machining operation, and an ejecting position, a rack and pinion for operating said stop, a cam and follower lever for operating said plate clamps, a shaft mounted on the machine frame and bearing said pinion and said cam, and a handle for moving said shaft, one movement of said handle and shaft being effective to operate said plate clamps by means of said cam and follower lever for clamping the plate to said member and simultaneously to adjust said stop by means of said rack and pinion from its plate locating position to its operating position, another movement of said handle and shaft being effective to operate said plate clamps for unclamping the plate and simultaneously to adjust said stop from its operating position to its ejecting position whereby the plate is ejected from the rotatable member.

8. In a machine for finishing tubular stereotype printing plates and having a frame and a cutting tool which engages the inner surface of the plate, the combination comprising, an annular sleeve rotatably supported on the machine frame and having an inside diameter at least as large as the outside diameter of the tubular plate, means for clamping the plate to said sleeve with its outside surface against the inside of the sleeve, and means for driving said sleeve so that the clamped plate turns about its longitudinal axis wherein the inner surface may be machined by said cutting tool, said last-named means including a shaft mounted on the machine frame and supporting a sprocket, a sprocket encircling said sleeve, and a chain drive trained around said sprockets for coupling said shaft and said sleeve.

9. In a machine for finishing tubular stereotype printing plates and having a frame, and a plurality of cutting tools for performing machining operations on a plate supported on the frame, the combination comprising, a rotatable member mounted on the machine frame for supporting the plate for rotation about its longitudinal axis so that the inside of the plate may be machined to a specified diameter by means of one of said cutting tools, said

13

cutting tool being movable axially of the plate as it turns, plate stop means mounted on the machine frame for and adapted to be positioned in abutting relation with the plate at one end when it is supported in the rotatable member, means connecting said rotatable member and said plate stop means for locking said rotatable member rigidly against rotation, so that plate lock-up means may be machined along the straight edges of the plate by means of another of said cutting tools, said cutting tool being movable axially of the plate and toward the end abutting the plate stop means so that the plate is held rigidly and against rotary movement by the rotatable member and the plate stop means.

10. In a machine for finishing tubular stereotype printing plates and having a frame and a plurality of cutting tools which engage the inner surface of the plate, the combination comprising, a rotatable member mounted on the machine frame for supporting the plate for rotation about its longitudinal axis so that the inside of the plate may be machined to a specified diameter by one of said cutting tools, means for driving said rotatable member, and means for locking said rotatable member rigidly against rotation in a predetermined angular position so that plate lock-up grooves may be accurately located and cut in the inner surface of the plate adjacent its straight edges by another of said cutting tools, said means being selectively operable.

11. In a machine for finishing stereotype printing plates and having a frame, means for supporting the plate on the machine frame including a rotatable sleeve, and means for clamping the plate in said sleeve, means for locking said sleeve against rotation so that the plate is held rigidly for machining, said means for locking said sleeve against rotation comprising a stop plate pivotally mounted on the machine frame for movement towards and away from said sleeve, an index pin supported on said stop plate, said sleeve having an index pin socket for receiving the said index pin when the sleeve is in a predetermined angular position and upon pivotal movement of the stop plate towards the sleeve.

12. In a machine for finishing stereotype printing plates uniformly curved about an axis, said machine having a frame, the combination comprising, means for rotating a plate about its axis on the machine frame for machining including a rotatable sleeve for holding the plate, means for clamping the plate in said sleeve, and means for locking said sleeve against rotation so that the plate is held rigidly for machining.

13. In a machine for finishing tubular stereotype printing plates and having a frame, the combination comprising, means for supporting the plate for rotation about its longitudinal axis including a cylindrical support member mounted for rotation on the frame, means for clamping said plate to said member including plate clamp members, and resilient means urging said plate clamp members into engagement with said plate, a lever movably mounted on said support member for operating said plate clamp members against the force of said resilient means for withdrawing said plate clamp members out of engagement with the plate and unclamping the plate, means for moving said lever including an actuating arm pivotally supported on the machine frame for movement transverse to the axis of the cylindrical support member and engagement with said lever when said support member is in a predetermined angular position, and means for locking said support member against rotation in said position.

14. In a machine for finishing tubular stereotype printing plates and having a frame, and a plurality of cutting tools for performing machining operations on a plate supported on the frame, the combination comprising, a rotatable member mounted on the machine frame for supporting the plate for rotation about its longitudinal axis so that the inside of the plate may be machined to a specified diameter by means of one of said cutting tools, means for clamping said plate to said member, means

14

operable when said rotatable member is in a predetermined angular position for unclamping the plate, means on the machine frame for locking said rotatable member against rotation in said predetermined position, and plate stop means mounted on the machine frame and adapted to be positioned in abutting relation with the plate at one end when it is supported in the rotatable member so that grooves may be machined along the straight edges of the plate by means of another of said cutting tools, said latter cutting tool being movable axially of the plate and toward the end abutting the plate stop means.

15. In a machine for finishing stereotype printing plates and having a frame, the combination comprising, means for supporting the plate on the machine frame for rotation about its longitudinal axis so that the inside of the plate may be machined to a specified diameter, said means including a rotatable sleeve, means for clamping the plate in said sleeve including plate clamp members, means pivotally mounted on the frame and selectively operable when said sleeve is in a predetermined angular position to move into engagement with said plate clamp members to actuate the same to clamp or release the plate, means on the machine frame for locking said sleeve against rotation in said predetermined position and plate stop means mounted on the machine frame and adapted to be positioned in abutting relation with the plate at one end when it is supported in the sleeve so that the plate is held rigidly for machining grooves adjacent the straight edges of the plate by means of a cutting tool moved axially at the plate and toward the end abutting the plate stop means.

16. In a machine for finishing tubular stereotype printing plates and having a frame, the combination comprising, means for supporting a plate on the machine frame for rotation about its longitudinal axis so that the inside of the plate may be machined to a specified diameter, said means including a rotatable sleeve, means for clamping the plate in said sleeve including plate clamp members, means operable when said sleeve is in a predetermined angular position for operating said plate clamp members, and means on the machine frame for locking said sleeve against rotation in said predetermined position so that the plate is held rigidly for machining grooves adjacent the straight edges of the plate, and following the machining operations said plate may be unclamped to permit removal of it from the sleeve, said means for locking said sleeve against rotation comprising a block pivotally mounted on the machine frame for movement towards and away from said sleeve, an index pin supported on said block, said sleeve having an index pin socket for receiving the said index pin when the sleeve is in said predetermined angular position and upon pivotal movement of the block towards the sleeve.

17. In a machine for finishing tubular stereotype printing plates and having a frame, the combination comprising, a rotatable member mounted on the frame for supporting the plate, and means on the frame for driving said rotatable member, said last-named means including a power shaft, a drive between said power shaft and said rotatable member, and a brake on said power shaft to hold said member against rotation.

18. In a machine for finishing tubular stereotype printing plates and having a frame and a plurality of cutting tools which engage the plate, the combination comprising, a rotatable member mounted on the machine frame for supporting the plate, means for driving the member for cutting off the end of the plate and for machining the inside of the plate with certain of said cutting tools as it turns, and for holding the member against rotation, means clamping the plate to the rotatable member, said plate being supported for rotation about its longitudinal axis and in a predetermined axial position so that the plate may be cut off to a given length by one of said cutting tools, and the inside of the plate may be machined to a specified diameter by another of said cutting tools,

means mounted on the machine frame for driving said rotatable member, and means on the machine frame for locking said rotatable member against rotation so that plate lock-up devices may be machined along the straight edges of the plate by other of said cutting tools as the plate is held against movement.

19. In a machine for finishing tubular stereotype printing plates and having a frame, the combination comprising, means for supporting a plate for rotation about its own axis including a member rotatably mounted on the frame, said member defining a cylindrical reference surface, means carried by the member for clamping the plate against said surface for rotation with said member, a plate stop movably mounted on said frame for movement longitudinally of said member in a path contiguous to the cylindrical reference surface, said stop having a first position adjacent one end of said member for engagement by one end of the plate for stopping the plate at a given machining location within the rotatable member, and means for moving said stop longitudinally from said first position to a position inside said supporting member for engaging and ejecting said plate therefrom.

20. In a machine for finishing tubular stereotype printing plates and having a frame, the combination comprising, means for supporting a plate for rotation about its own axis including a member rotatably mounted on the frame, said member defining a cylindrical reference surface, means carried by the member for clamping the

plate against said surface for rotation with said member, a plate stop movably mounted on said frame, said stop having a plate locating position adjacent the end of the supporting member and the rough surface wherein it is engaged by one end of the plate and the plate is accurately positioned lengthwise of its own axis relative to the supporting member, and a plate ejecting position inside said member and adjacent the rough surface, and means for moving said stop between its positions, said stop being effective to eject said plate from the member upon movement to the ejecting position.
